UNITED STATES PATENT OFFICE.

ETTORE BONAZZI, OF MONTPELIER, VERMONT.

STONE-DRESSING TOOL.

Application filed February 18, 1925. Serial No. 10,039.

This invention relates to an improved tool for dressing stones, the same being especially, although not necessarily, primarily intended for working down and finishing off comparatively rough parts of marble and granite to be used in the production of monuments and the like.

In order that a clear understanding of the invention may be had, it is deemed advisable 10 to briefly consider the manner of treating stones of this class. To this end, it is to be stated that in the progress of manufacturing rough granite into monuments, the stones as they come from the quarries are squared 15 by means of discs and planed, or are sawed or pointed with a surface cutter, in some instances the pointing being done by hand.

The second step, if the stone is to be hammered, is to have it hammered by a hand 20 operated implement or hammered under a surface cutter. If the stone is to be polished, it must be carried to a polishing mill, where the surface is moved down with an ironing wheel in which shot is used. Secondly, a 25 thin scroll is frequently used with compound abrasive. Finally, to bring out a high polish, a buffer is used, the entire method of polishing and hammering being performed on a smooth surface.

30 The foregoing method of treating stone, which is a practice which appears to be uniform in most modern monumental work, is unduly long and exceedingly expensive, requiring the skilled service of numerous employees.

35 After thoroughly explaining the difficulties arising from the conditions specified, I have evolved and produced a means which enables practically the entire work enumerated 40 to be done with approximately three tools, the fundamental principle of construction of which is the same in all instances.

The primary tool is of steel, the same being high adaptable for treating stone in the 45 first stages. The second tool is an abrasive tool, the same serving to bring on a more plane surface, and the remaining tool is a buffer used for finishing the already smooth surface.

50 The invention not only has reference to the improved tools for dressing the stone, but relates also to a novel purpose which is followed to insure accomplishment of the most effective result possible through the use of 55 the improved tools.

The method referred to and the improved

tools will be rendered more clear upon carefully considering the following description in connection with the accompanying drawing wherein:

60 Figure 1 is a side elevation of the primary steel tool employed in the initial operations upon the stone, the generic principle of construction being here illustrated.

Fig. 2 is a detail view of one of the disks 65 utilized in the construction of the tool shown in Fig. 1.

Fig. 3 is a side elevation of the disk prior 70 to reducing it to the shape exhibited in Fig. 2.

Fig. 4 is a perspective of a spacing washer constituting a part of the improved tool.

Fig. 5 is a side elevation of the washer before it is bent.

Fig. 6 is a diagrammatic illustration showing 75 the method of operation.

Fig. 7 is a view, on reduced scale, like Fig. 1, showing an abrasive tool.

As before stated, the invention in its broadest aspect comprises the three tools 80 specifically referred to, to be used in the manner enumerated and considered generally the principle of construction of each tool is precisely the same.

In other words, the general principle upon 85 which each tool is made is that it is of spiral formation so that upon setting it into rotation it constitutes a cutting screw serving to smooth the surface and carry the cuttings off.

90 Attention is first confined to Fig. 1 wherein it will be seen that an appropriate shaft 1 is shown. Seated upon this shaft is a spiral hub. The hub in the present instance is made up of a plurality of individual spacing 95 washers 2, shown in detail in Figs. 4 and 5. These washers are of bendable steel and in practice each washer, which is comparatively wide, is slit transversely as indicated at 3 in Fig. 5. The free ends 4 are then bent away 100 from each other in opposite directions and the washers are somewhat contracted in circumference. The several washers are placed in a series on the shaft 1 as clearly illustrated in Fig. 1 to form the hub which actually 105 provides a spiral groove extending from end to end.

110 Located in this groove is a spiral cutter. While the cutter could be constructed otherwise, it is preferably made of individual steel disks 5 shown in detail in Figs. 2 and 3. The disks, like the washers, are slit on

one side as at 6, the slit extending through the periphery and permitting the adjacent free ends to be twisted or bent away from each other as at 7. The adjacent disks and washers 2 are arranged in abutting relation and the inner portions of the disks are confined in the spiral grooves provided between the washers 2.

Both the disks and washers are formed at 10 predetermined points with keyways 8 for the reception of a key (not shown) carried by the shaft to securely anchor the surfacing means of said shaft. Manifestly when deemed expedient the frictional contact between 15 said key 8 and the shaft, disks and washers may be depended upon to hold the disks and washers in assembled relation. In assembling, a disk 5 is placed on the shaft, then a washer 2, then another disk, another 20 washer, and so on. The washers may vary in width to vary the spaces between the disks to permit a finer or coarser shave of the stone surface.

Noting now the abrasive tool shown in 25 Fig. 7, it will be seen that the disks 9 there shown are simply of abrasive material, the construction being the same as that described for the steel disk 5. The spacing washers 2 are identical, being useable with either the 30 steel or abrasive disks. The shaft 1 is the same. Hence, the same reference characters used for these two parts.

Although it has not been shown, the third 35 tool, known as a buffer, may be of the same construction except that the peripheries of the disks may be of felt or other equivalent material. Although the peripheries of the disks have been shown of particular configuration in the two instances illustrated, it is 40 to be understood that the shape may be varied according to the grade of stone being acted on.

In use, the blocks of stone S are moved by an appropriate table or the like (not shown) in the direction of the straight arrows, Figure 6, while the shaft of the cutter, which is driven by a suitable machine, is rotated in the direction of the curvilinear arrow. The movement of the stone is in one direction and the rotation of the cutter is in an opposite direction. Not only this, but the cutter is disposed at a diagonal angle across the surface of the stone rather than at a true right angle. This facilitates the movement and ready cutting and the smooth surfacing of the same.

It is thought that the foregoing description taken in connection with the drawings, will enable persons skilled in the art to which the invention relates to obtain a clear understanding of the same. For this reason, a more lengthy description is thought unnecessary.

While the preferred embodiment of the invention has been shown and described, it is to be understood that minor changes coming within the field of invention claimed, may be resorted to if desired.

Having thus described my invention, what I claim as new is:

A tool comprising a shaft, a plurality of spaced spiral disks about the shaft, each disk having a central opening and a slot extending from said opening to its periphery, and the ends of the disk at opposite sides of the slot being spaced from and disposed at opposite sides of the plane of the major portion of the disk, spiral split washers arranged about the shaft and between the disks, and means holding the disks and washers to the shaft.

In testimony whereof I affix my signature.

ETTORE BONAZZI.
